E. VON SALIS

FUEL INJECTION DEVICE FOR SOLID OIL ENGINES

Original Filed Nov. 12, 1924

INVENTOR

Edward von Salis

BY

Jerry, Richard E., Esq.
ATTORNEY

UNITED STATES PATENT OFFICE.

EDUARD VON SALIS, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

FUEL-INJECTION DEVICE FOR SOLID-OIL ENGINES.

Application filed November 12, 1924, Serial No. 749,376, and in Switzerland January 24, 1924. Renewed January 12, 1928.

The invention relates to a fuel injection device for solid oil engines, its object being to produce adequate and substantially constant fuel injection velocity whatever the amount of the charge and under all engine requirements. This object is accomplished by providing in combination with a variable delivery oil pump an accumulator chamber connected thereto and to the engine injection nozzle and having an accumulator plunger whose inward movement is limited by a relatively fixed abutment, the beginning of the fuel injection being determined by mechanical means and its end by said abutment, the charge, whatever its amount, being thereby injected at an adequate and substantially constant injection velocity. This and other advantages of the invention will appear to those skilled in the art from the following specification.

Referring to the drawing, the single figure illustrates diagrammatically in cross-section the preferred embodiment of the invention, a usual variable delivery fuel pump being shown on a smaller scale at the left of the drawing.

In the form of the device illustrated, 1 is a variable delivery fuel pump which by the pipe 2 delivers to the accumulator chamber 3, in which is located the plunger 4 having a wide or flanged head 5 and forced inward against the relatively fixed abutment 6 by the accumulator spring 7 reacting between the plunger and the thrust plate 8 adjustable by the set screw 9 in the top of the accumulator chamber, which set screw is provided with a lock nut 10. The spring is centered by the cylindrical projections 11 and 12 on the plunger and thrust plate respectively.

Exit of oil from the accumulator chamber 3 and the beginning of injection is determined by mechanical control of the valve 13 seated against the outlet from said accumulator by the spring 14, reacting against the cap 15. This valve is opened periodically by a cam lever 16, one of whose arms is operatively associated with the valve while the

other carries a cam roller 17, the lever being actuated by the cam 18 on shaft 19 which is in phase with the crank shaft of the engine, the arrangement being such that the valve is closed by the spring at any time after the plunger has completed its inward movement. The valve controlled opening by duct 20 delivers the charge to the engine injection nozzle 21 which, in the illustrated embodiment, is closed by a fuel-opened valve 22 and seated by a spring 23, thus preventing combustion products from the engine cylinder 24 from being driven into the duct 20 and leaving deposits of carbon therein.

With the arrangement described it will be apparent that the loaded accumulator ends its delivery stroke always at the same point and that whatever the quantity of the charge it is, when the outlet valve of the accumulator chamber is opened, forcibly ejected therefrom and injected into the engine cylinder at a sufficiently high and substantially constant fuel injection velocity whereby a properly extended distribution and intimate mixture of the injected oil particles with the compressed air in the cylinder is effected, notwithstanding the variations in engine requirements and consequent changes in the amount of fuel delivered at different times.

I claim:

1. Means for producing substantially constant fuel injection velocity in solid oil engines comprising in combination a variable delivery oil pump, an accumulator chamber connected thereto and to the engine injector nozzle and having an accumulator plunger, a spring loading said plunger, and means for controlling communication between said chamber and the injection nozzle including a valve and timed means for periodically opening it, the accumulator plunger having an abutment adapted to move inward against a relatively fixed abutment before the valve closes, thereby terminating the delivery of the fuel to the engine injection nozzle, said nozzle having a fuel valve to control the delivery of fuel into the

engine cylinder automatically opened by pressure of the fuel delivered by the accumulator, and closed by spring pressure on cessation of such delivery.

5. 2. Means for producing substantially constant fuel injection velocity in solid oil engines as set forth in claim 1, and in which

the valve controlling communication between the accumulator chamber and the injection nozzle is held to its seat by fuel **10** pressure from the accumulator.

In testimony whereof, I have signed this specification.

EDUARD von SALIS.
